AU 33503/63 1/1966

1 Claim, 4 Drawing Sheets

FIG. 1 is a perspective view of the fencing component;

FIG. 2 is a top plan view of the fencing component;

FIG. 3 is a first end view of the fencing component;

FIG. 4 is a second end view of the fencing component;

FIG. 5 is a side view of the fencing component;

FIG. 6 is a side cross-sectional view of the fencing component, as taken along the plane indicated in FIG. 2; and,

FIG. 7 is a bottom view of the fencing component.

FIG. 2.

FIG. 3.

FIG. 4.

FIG. 5.

FIG. 6.

FIG. 7.
